UNITED STATES PATENT OFFICE.

WILLIS S. CRANDELL, OF ELSMERE, NEW YORK.

PAPER-MAKING MACHINE.

Application filed April 29, 1921. Serial No. 465,391.

To all whom it may concern:

Be it known that I, WILLIS S. CRANDELL, a citizen of the United States, residing at Elsmere, in the county of Albany and State 5 of New York, have invented certain new and useful Improvements in Paper-Making Machines, of which the following is a specification.

This invention relates to paper-making machines of the type employing a cylinder of wire cloth rotating in the vat containing the pulp-bearing liquid, for the initial formation of the web of paper.

One of the objects of my invention is to 15 enable a heavier couch roll than is customarily used in such machines to be employed to take the newly-formed web of paper from the rotating cylinder.

In the type of machine here referred to, 20 the couch roll has customarily been mounted in bearings above the cylinder mould upon lever arms to press downwardly upon the upper surface of the cylinder, the couch roll being generally rotated in this position in 25 contact with the cylinder by the endless apron or band of felt which is designed to transport the newly-formed web of paper from the couch roll to other parts of the machine.

30 In paper-making machines of the type herein referred to, it has been found necessary to make the cylinder mould of as light a construction as possible and having as few moving internal parts as possible in order that there may not be too great a commotion 35 of the fibre-bearing liquid in the vat upon the rotation of the cylinder. Because of this light and simple construction of the cylinder, it is impossible to sustain a heavy 40 weight thereagainst, so that the couch roll pressing upon the upper surface of this cylinder has been, of necessity, made of an extremely light construction, generally being made of a hollow cylinder of light material 45 covered with rubber.

Among the well-known functions of the couch roll are to take the newly-formed and extremely wet web of paper from the cylinder mould and to transfer it to the long band 50 of felt which transports the paper to the pressing rolls and thereafter to the other parts of the machine, and during this operation of taking the newly-formed web from the cylinder mould, to perform an initial 55 pressing operation to press some of the ex-

cess water therefrom. Because of the light construction of the couch roll heretofore found necessary, as already stated, this roll was enabled to perform to a substantial degree only the function of transferring the 60 newly-formed web of paper from the cylinder mould to the felt band or carrier and was not enabled to perform to any substantial degree the function of a press roll.

One of the objects of my invention is, 65 therefore, to overcome the defect here noted in machines of this type and to permit a heavier couch roll to be used in contact with the cylinder mould than has heretofore been used.

Another object of my invention is to provide such bearings for the support and engagement and operation of the couch roll and the cylinder mould that not only may a heavier couch roll be employed, and for the 75 accomplishment of the objects heretofore stated, but that a couch roll may be employed performing the additional functions of the first presser roll as customarily performed. In machines of the prior art, as already stated, the light-weight couch rolls are not relied upon to initially press excess water from the newly-formed web, and the web, with the excess water therein as received from the cylinder mould, is immediately 80 transferred by the couch roll to the long band of felt which transports it to the first presser rolls, located at a substantial distance from the cylinder mould and couch roll. By providing a sufficiently heavy 85 couch roll to perform the additional function of a presser roll, my invention further contemplates the location of the co-operating presser roll of the first presser rolls in engaging contact with the combined couch and 90 presser roll, the two to perform the customary functions of the first presser rolls. Such a construction and arrangement of parts provides a more compact machine than 95 when the presser rolls are located at a distance from the cylinder mould and couch roll and also dispenses with the long band of felt required to transport the web of paper from the couch roll to the presser rolls, features of extreme importance in the saving of floor space.

Another object of my invention is to provide a support for the cylinder mould adjustable to enable just that surface contact 105 between the cylinder mould and the couch 110

roll required for most efficient results in driving the cylinder mould and in the removal of the web formed thereon to the couch roll.

5 These and other objects of my invention will more fully appear from an illustrative embodiment thereof set forth in the following specification and the accompanying drawings, but it is to be understood that my 10 invention is capable of embodiment in many different forms. While, therefore, I shall illustrate my invention by the best embodiment known to me, such embodiment is to be regarded only as typical of many possible 15 embodiments and my invention is not to be confined thereto.

In the drawings like characters of reference denote corresponding parts throughout all the views,—of which—

20 Figure 1 is a side elevation of a cylinder paper-making machine embodying my invention;

Fig. 2 is a plan view of that portion of Fig. 1 showing the pulp vat, the cylinder mould therein and the couch roll mounted thereabove, but with the couch roll removed;

Fig. 3 is a plan view similar to Fig. 2 and showing the couch roll with its bearings;

30 Fig. 4 is a sectional view along the line 4—4 of Fig. 2 and showing a detail of the adjustable mounting for the cylinder mould;

Fig. 5 is a similar sectional view along 35 the line 5—5 of Fig. 2;

Fig. 6 is a plan view of the free extremity of one of the lever arms of the cylinder mounting, later to be referred to, and

Fig. 7 is a side elevation similar to Fig. 40 1 but showing the couch roll in engagement with the presser roll shown in Fig. 1 as distantly located from the couch roll.

In Fig. 1 the numeral 1 indicates the pulp vat, having the dam 2 forming a 45 shallow semi-cylindrical passage about the cylinder mould 3, all of the usual construction.

The couch roll 4 is mounted in bearings 50 5 upon rigid standards 6, one on each side of the vat.

The cylinder mould is mounted in adjustable and spring-pressed bearings so as to be spring-impelled against the couch roll, but the cylinder mould does not sustain the 55 weight of the couch roll, due to the self-sustaining mounting of that roll as heretofore described.

60 Preferably, the mounting for the cylinder mould, and as shown in the illustrative embodiment, comprises lever arms 7, one at each side of the interior of the vat 1, separately journaled for pivotal movement upon an axis 8 fixedly mounted in lugs 9 extending from an interior end wall of the 65 vat 1, as shown in Figs. 2 and 3. Each of

these lever arms has a depending portion 10 substantially midway thereof and immediately beneath and in line with the bearing of the couch roll, the lower extremity of such depending portion forming on each 70 side of the interior of the vat a bearing in which the axle 11 of the cylinder mould is journaled at each end.

At its free extremity, the left end as shown in Fig. 1, each of the lever arms 7 75 is upwardly curved to extend above the vat, its extremity terminating in a straight horizontally-disposed portion, as shown in Fig. 1.

The extremity of each of the lever arms 80 7 has a circular aperture 12 therethrough, indicated by dotted lines in Fig. 1 and shown in plan in Fig. 6, and a shallow groove across the arm forming a recess 13, 85 square in cross-section, as shown in Fig. 6.

A plug having a cylindrical lower portion 14 and a square head 15 is designed to be inserted in the aperture and recess referred to of the arm 7, the longer cylindrical portion 14 of the plug fitting loosely in 90 the circular aperture 12 in the arm, and a square head 15 of the plug fitting in the shallow recess 13 in the upper surface of the arm 7, as shown in Fig. 5. In this position it is obvious that the plug cannot 95 be rotated in the arm 7 due to the engagement of the square head 15 with the sides of the square recess 13 in the arm, but that when the plug is elevated a sufficient distance to cause the shoulder between the head 15 and the cylindrical portion 14 to clear the shallow groove 13, the plug can be rotated, the lower cylindrical portion 14 then turning in the aperture 12, and a handle 16 is provided for such rotation.

100 The plug 14 has an aperture, circular in cross-section, large enough for the insertion of a screw 18 and to permit a free vertical movement of the screw. The screw 18 is designed for such vertical movement relative to the plug 14 but is prevented from rotation therein by a pin 19 secured thereto and traversing a vertical groove 20 in the plug. From this construction it is obvious that when the plug 14 is mounted in 105 its lowest position in an arm 7 so that the square head 15 is seated within the squared recess 13 of the arm, rotation of the plug and hence of the screw relative to the plug is not possible, although a vertical movement of the screw 18 relative to the plug is possible, but that when the plug is elevated sufficiently to clear the head 15 from the recess 13 in the arm, a rotation of the plug will correspondingly transmit a rotation to 120 the screw. A slight upward lift by the handle 16 and then a rotation of the handle will free the plug and perform the rotative movement referred to.

125 Each of the arms 7 is provided with a de- 130

pending portion 21 from which extends a horizontal bearing support 22. In the depending portion 21 is journalled a shaft 23, extending entirely across the space between 5 the two arms and journalled in both arms, as shown in Fig. 2. In the horizontally extending bearing portion 22 of the arm 7 referred to, is an aperture 24 through which the screw 18 loosely extends, and about this 10 aperture is a bearing 25 upon which is mounted a worm-wheel 26, the worm-wheel having an axial screwthreaded aperture, the threads of which engage the threads upon the screw 18. Upon the shaft 23 are two 15 worms 27 adjacent the two worm-wheels 26 upon the two arms 7, and engaging these worm-wheels. Rotative movement is imparted to the shaft 23 by a handwheel 23^a.

It is obvious from the construction here- 20 tofore described, that when the shaft 23 is rotated by the hand-wheel 28, the worms 27 thereon rotate the worm-wheels 26, and these worm-wheels being themselves prevented from vertical movement and being 25 in screw-threaded engagement with the screw 18, impart a vertical movement to the screws 18, when those screws are held from rotation by the head 15 of the plug being seated in the squared recess 13.

30 Mounted upon the pulp vat at each of the corners immediately in line beneath the free end of each of the arms 7 is a supporting block 28 bearing an open-ended cylindrical casing 29 within which telescopes a corre- 35 spondingly cylindrical casing 30 with closed upper and open lower ends, and between which, and attached at its extremity to the two oppositely-disposed and telescoping casings is a spring 31, the upper casing 40 obviously being free to move relative to the stationary casing 29 and impelled upwardly by the pressure of the spring 31.

The closed upper end or cap of the movable casing 30 has a centrally-disposed recess, designed to center the lower end of 45 the screw 18 by engagement therein.

From the construction and arrangement of parts thus described, it is obvious that the lever arms 7 are pivotally supported at 50 their right-hand extremities, as viewed in Fig. 1, and are supported at their left-hand extremities upon the spring-sustained casing 30 through the screw 18, and the various parts co-operating therewith already referred to. It is also obvious that by this 55 manner of support, the lever arms 7 are impelled by the spring 31 upwardly against the couch roll 4, so that the cylinder mould, supported in the depending portion of the 60 lever arms, is spring-impelled against the couch roll 4 and bears thereagainst only because of the pressure of the spring, and does not sustain any of the weight of the couch roll 4 or any pressure transmitted 65 therethrough.

It is also obvious that the spring tension impelling the cylinder mould 3 against the couch roll 4 is capable of adjustment. An important feature of this adjustment is that a simultaneous adjustment of the spring tension impelling both arms 7 upwardly may be made, or an independent adjustment of such arms. By rotation of the shaft 23 by the hand-wheel 28, the simultaneous adjustment is accomplished through the medium of 70 the worms 27 engaging the worm-wheels 26, whereby the screw 18 is either elevated or lowered, depending upon the direction of rotation imparted to the shaft 23. If the screw 18 is moved vertically upwardly relative to the extremity of an arm 7 and a plug 14 therein, the tension on the spring 31 is lessened, and if the screw 18 is lowered relative to the arm 7 and the plug 14 therein, the tension on the spring 31 is increased. 80 If an independent adjustment of the spring tension upon one lever arm is desired independently of the other, the plug 14 in that arm is elevated by the handle 16 until the squared head is freed from the shallow 85 recess 13 in the arm, and then the plug is rotated by the handle, thus imparting rotation to the screw 18. As the worm-wheel 26, when not rotated by the worm 27 and shaft 23, is incapable of either vertical or rotative movement, the rotation of the screw 18 imparted by rotation of the plug 14, necessarily lowers or elevates the screw 18, thus accomplishing an adjustment 90 of the tension of the spring 31, entirely independent of the adjustment through rotation of the worm-wheel 26.

This independent adjustment is of extreme importance in maintaining the desired pressure of the cylinder mould against 105 the couch roll across the entire face of the cylinder mould.

It has heretofore been customary, and particularly where a light couch roll has been employed, to drive the couch roll by the endless felt band, and to independently drive the cylinder mould. Such drives may be employed in my present invention, but I preferably drive the couch roll independently of the felt band thereabout, a driving 110 gear 32 being illustrated in Fig. 3 as secured upon the axle of the couch roll 4, which gear, it will be apparent, may be driven by the usual train of gears and other driving mechanism employed in such machines, or, if desired, a pulley may be secured to the axle of the couch roll 4, and the same be driven by the usual belt from the prime mover or any other rotating part. The cylinder mould, in the illustrative embodiment 115 of my invention, I preferably drive by its spring-pressed engagement with the couch roll.

In the operation of my invention as thus described, and as illustrated in Fig. 1, the 120 125 130

usual endless band of felt 33 is employed travelling in the direction of the arrow and passing between the couch roll and the cylinder mould and from thence between the 5 presser rolls indicated generally by the numeral 34, these presser rolls being of the usual type, located at a distance from the couch roll as shown. The initial web of paper formed by the cylinder mould is taken 10 up by the couch roll and transferred to the felt carrier, and, because of the substantial construction of the couch roll and the pressure of the cylinder mould thereagainst, the couch roll functions to initially press some 15 portion of the excess water from the newly-formed web of paper.

Because of the substantial and heavy construction of the couch roll, possible because of the fixed support or bearing of the couch 20 roll and because the couch roll does not exert a pressure due to its weight upon the cylinder mould, if desired this couch roll may be employed to perform the additional function of a presser roll, and in Fig. 7 I 25 have shown one of the presser rolls 34, located in direct engagement with the couch roll 4, the couch roll 4 and the presser roll 34 thus performing the function of the pair of presser rolls 34 shown in Fig. 1 as 30 distantly located from the couch roll. By such an arrangement of parts as is shown in Fig. 7, the newly-formed web of paper is taken from the cylinder mould by the couch roll 4 in precisely the same manner 35 as in the construction shown in Fig. 1, a certain portion of the excess water pressed therefrom by the engagement of the cylinder mould with the couch roll, and this newly-formed web of paper, instead of being 40 transferred to a long felt band to be transported to distant presser rolls, is immediately passed between the upper surface of the couch roll 4 and the under surface of the presser roll 34, and the excess 45 water pressed therefrom in the same manner as is done by the distantly located presser rolls 34 in Fig. 1, and from between the presser roll 34 and the couch roll 4, now combining the functions of a couch and a 50 presser roll, the web of paper is transferred in the usual manner to other parts of the machine such as the drying rolls and the calendering rolls. By the arrangement shown in Fig. 7, I am, therefore, enabled 55 to dispense with the long felt band, and to compact the machine, thus saving floor space, by combining in the couch roll the additional function of a presser roll and associating the co-acting presser roll im- 60 mediately thereabove.

With the location of the presser roll as shown in Fig. 7, it is desirable that some means be provided to dispose of the excess water which is carried up over the combination couch and press roll, the roll 4 in

Fig. 7, and in practical use, well-known types of press rolls may be employed having a suction device for drawing the water through the cylindrical surface of the press roll. It will also be understood that where 70 a press roll is employed in direct engagement with the couch roll, as shown in Fig. 7, and where the couch roll has a metallic surface, the co-acting press roll may be jacketed or otherwise constructed to present a non-metallic surface, both to avoid difficulties in the wear of the two surfaces and to permit the transfer of the pressed 75 web of paper from the couch roll.

It is to be understood that in all the arrangements of the parts, both as illustrated in Fig. 1 and as illustrated in Fig. 7, the spring-mounted and adjustable bearing for the cylinder mould is used, and the spring adjustment referred to may be such that the 80 cylinder mould is pressed against the couch roll only to a sufficient extent to receive motion from the couch roll, and, therefore, as already stated, the weight of the couch 85 roll is entirely immaterial. 90

I claim:

1. In a cylinder paper machine, the combination of a cylinder mould and a couch roll, bearings for said cylinder mould and couch roll adapted to permit rotative movement of said parts in surface engagement one with another, adjusting means associated with the bearings of one of said parts providing an adjustment of said part bodily toward or away from the other said part, 95 and like associated but independently operable adjusting means providing a like adjustment of end portions of said part.

2. In a cylinder paper machine the combination of a rotatable cylinder mould and a 100 rotatable couch roll, a plurality of springs adapted to exert pressures at separated points measured along the axis of one of said rotatable parts and tending to urge said rotatable part into engagement with the other said rotating part and means for simultaneously adjusting the tension of said springs.

3. In a cylinder paper machine, the combination of a rotatable cylinder mould and a 105 rotatable couch roll, a plurality of springs adapted to exert pressures at separated points measured along the axis of one of said rotatable parts and tending to urge said rotatable part into engagement with the other said rotatable part, adjusting means for simultaneously varying the tension of said springs and adjusting means to independently vary the tension of said springs. 110

4. In a cylinder paper machine, the combination of a cylinder mould and a couch roll, a plurality of springs adapted to exert pressures at separated points measured along the axis of said cylinder mould tending to urge said cylinder mould into engagement 115 120 125 130

with said couch roll and means for simultaneously adjusting the tension of said springs.

5. In a cylinder paper machine, the combination of a cylinder mould and a couch roll, two springs adapted to exert pressures at separated points measured along the axis of said cylinder mould tending to urge said cylinder mould into engagement with said couch roll, and means for simultaneously or independently adjusting the tension of said springs.

6. In a cylinder paper machine, the combination of a cylinder mould and a couch roll, an immovable bearing entirely supporting said couch roll, a movable bearing for said cylinder mould, two springs adapted to exert pressures upon said movable bearing at separated points measured along the axis of said cylinder mould tending to urge said cylinder mould into engagement with said couch roll, and means for simultaneously or independently adjusting the tension of said springs.

25 7. In a cylinder paper machine, the combination of a cylinder mould and a couch roll mounted upon axes in the same plane for rotative movement in surface engagement one with the other along a line in said plane, spring means exerting pressures at a plurality of points along the axis of one of said rotative parts urging said rotative part into said surface engagement with the other said rotative part, adjusting means associated with said spring means to adjust the tension of said spring means to vary the pressures equally along said axis and like associated but independently operated adjusting means to vary the tension of said spring means to unequally vary the pressures along said axis.

8. In a cylinder paper machine, the combination of a cylinder mould and a couch roll mounted upon axes for rotation in surface engagement one with the other, immovable bearings entirely supporting said couch roll, a floating bearing for each of the opposite ends of said cylinder mould, a spring supporting each bearing, adjusting means for simultaneously varying the tension of said springs in like degree and adjusting means for independently varying the tension of said springs.

55 9. In a cylinder paper machine, the combination of a cylinder mould and a couch roll mounted upon axes for rotation in surface engagement one with the other, immovable bearings entirely supporting said couch roll, separate lever arms and bearings adapted to journal said cylinder mould at each of its opposite ends, a spring engaging each of said lever arms and tending to move said cylinder mould toward said couch roll, adjusting means to simultaneously vary the tension of said springs including a rod

mounted in said lever arms for movement to operate said adjusting means and means for manually moving said rod.

10. In a paper machine, an adjustable mounting for a rotating cylinder comprising two spaced pivoted lever arms, bearings therein for the opposite ends of the cylinder, a movable supporting member for each of said lever arms, a spring for each of said supporting members adapted to sustain said members and tending to move said members upwardly, rigid adjusting members, one mounted upon each of said lever arms, and extending to and bearing upon said supporting members to support said lever arms from said supporting members, and means for moving said adjusting members relative to said lever arms to vary the distance between said lever arms and said supporting members measured along said adjusting members.

11. In a paper machine, an adjustable mounting for a rotating cylinder comprising two spaced pivoted lever arms, bearings therein for the opposite ends of the cylinder, a movable supporting member beneath each of said lever arms, a spring for each of said supporting members adapted to sustain said members and tending to move them upwardly, rigid adjusting members, one mounted upon each of said lever arms and extending to and bearing upon said supporting members, and means for moving said adjusting members relative to said lever arms to vary the distance between said lever arms and said supporting members measured along said adjusting member.

12. In a paper machine, an adjustable mounting for a rotating cylinder comprising two spaced pivoted lever arms, bearings therein for the opposite ends of the cylinder, a movable supporting member beneath each of said lever arms, a spring for each of said supporting members adapted to sustain said members and tending to move them upwardly, rigid adjusting members, one mounted upon each of said lever arms and extending to and bearing upon said supporting members, manually operable means for simultaneously moving said adjusting members relative to said lever arms to equally vary the distances between said lever arms and said supporting members measured along said adjusting members, and manually operable means to independently move said adjusting members to unequally vary said distances.

13. In a paper machine, an adjustable mounting for a rotating cylinder comprising two spaced lever arms pivoted at one end, bearings thereon at an intermediate point to journal the opposite ends of the cylinder, a movable supporting member beneath each of the free ends of said lever arms, a spring for each of said supporting

members adapted to sustain said members and tending to move them upwardly, adjusting screws, one for each of said lever arms, mounted on said lever arms and extending downwardly to supported contact upon said supporting members, worm wheels, one mounted on each of said lever arms in screw-threaded engagement with said screws, a shaft extending across and journaled for rotation in said lever arms, worms on said shaft engaging said worm wheels to rotate the same, means manually operable for rotating said shaft and means for restraining rotation of said screws when said worm wheels are rotated, whereby said screws are moved in the direction of their length and relatively to said lever arms, when said worm wheels are rotated.

14. In a paper machine, an adjustable mounting for a rotating cylinder comprising two spaced lever arms pivoted at one end, bearings thereon at an intermediate point to journal the opposite ends of the cylinder, a movable supporting member beneath each of the free ends of said lever arms, a spring for each of said supporting members adapted to sustain said members and tending to move them upwardly, adjusting screws, one for each of said lever arms, mounted on said lever arms and extending downwardly to supported contact upon said supporting members, worm wheels, one mounted on each of said lever arms in screw-threaded engagement with said screw, a shaft extending across and journaled for rotation in said lever arms, worms on said shaft engaging said worm wheels to rotate the same, means manually operable for rotating said shaft and means for locking said screws against rotation but permitting linear movement when said worm wheels are rotated, and in-

dependently manually operable means for releasing each of said locking means and for rotating each of said screws when said worm wheels are not in rotation, enabling a linear adjusting movement of either of said screws independently of the other. 45

15. In a cylinder paper machine, the combination of a cylinder mould, a couch roll, an immovable bearing entirely supporting said couch roll, means entirely supporting said cylinder mould and pressing the same toward said couch roll, a felt apron passing around said couch roll, and a press roll co-operating with said couch roll. 50 55

16. In a cylinder paper machine, the combination of a cylinder mould, a roll adapted to perform the functions of a couch roll, an immovable bearing entirely supporting said roll, means entirely supporting said cylinder mould and pressing the same toward said roll, a press roll co-operating with said first mentioned roll, and a felt apron passing around said couch roll, said two rolls constructed and adapted to co-operate 60 65 to perform the function of press rolls.

17. In a cylinder paper machine, the combination of a vat and a cylinder mould disposed therein, a couch roll running in fixed bearings above said vat, a pair of levers pivoted in said vat and having their outer ends extending above the same, said levers embodying depending portions carrying bearings for said cylinder mould, supports for the outer ends of said levers, and adjusting 70 75 means for shifting the position of the outer ends of said levers with regard to their supports.

In testimony that I claim the foregoing, I have hereunto set my hand this 20th day of April, 1921. 80

WILLIS S. CRANDELL.
